UNITED STATES PATENT OFFICE.

OSCAR GERLACH, OF IOLA, KANSAS.

APPARATUS FOR TREATING CEMENT.

No. 894,825.

Specification of Letters Patent.

Patented Aug. 4, 1908.

Application filed October 14, 1905. Serial No. 282,785.

To all whom it may concern:

Be it known that I, OSCAR GERLACH, a citizen of the United States, residing at Iola, in the county of Allen and State of Kansas, have 5 invented certain new and useful Improvements in Apparatus for Treating Cement, of which the following is a specification, reference being had therein to the accompanying drawing.

10 This invention relates to improvements in the process and apparatus for treating cement.

Figure 1 is a view partly in side elevation and partly in section of a cement kiln embodying my improvements and suited for carrying out my process. Fig. 2 is an end view looking into the calcining end of the kiln, the casing which carries the apparatus for delivering fuel to the kiln being removed. 15 Fig. 3 is a section on the line 3—3, Fig. 1. Fig. 4 shows an enlarged longitudinal section of a portion of the rotary cylinder shell. Fig. 5 is a face view or end elevation of the elevating or lifting and carrying device for 20 withdrawing the clinker from the cooler, detached and on a larger scale, parts being broken away. Figs. 6, 7, 8 and 9 are detailed views of the same.

In the drawings 1 represents as an entirety 25 a rotary cylinder, preferably mounted with its axis inclined to the horizontal and supported in this position in any suitable manner. Power for rotating the cylinder may be supplied in any suitable manner. I have indicated driving devices for the cylinder comprising a gear wheel 1^a mounted concentrically on the cylinder and secured thereto and driven by a set of power transmitting devices indicated as an entirety by 1^b.

40 At its receiving end the cylinder opens into a large chamber 2 from which leads an exhaust chimney or stack 3. The material may be fed to the receiving end of the rotary kiln in any suitable manner; for illustration 45 I have shown a spiral conveyer for this purpose.

The interior lining of the cylinder casing 1' for the greatest part of its length from its receiving end to its calcining and delivery end 50 may be of any suitable and well known construction, and for the purpose of illustration I have indicated it as composed of bricks or blocks 5 of a material which is highly refractory to heat and laid up in the well known manner. At the delivery end of the kiln I 55 arrange a ring or annular block of such bricks

as indicated at 6. Between the ring 6 and the last annular row of bricks ahead of it within the cylinder casing I provide a lining or sheathing for the interior of the casing, as 60 indicated at 8; which preferably consists of a concrete composed of crushed clinker, cement grit and cement in proper proportions to produce the necessary binding action between the constituents. The clinker should 65 be crushed so as to consist of particles ranging anywhere from a quarter of an inch to three quarters of an inch in thickness and the cement grit should preferably be from a twenty-mesh screen, although these specifications may be varied as desired. A layer 70 of this concrete, substantially of the same thickness as the lining of bricks at either end of it is molded or formed within the cylinder casing in any preferred manner. The inner 75 surface of this concrete lining is then washed with a mixture of cement and feldspar or fluorspar, or any other material which may serve as a flux, which wash is adapted, when subject to high heat to produce a hard highly 80 refractory glaze upon the said lining and to provide a surface much more lasting than one formed of bricks with cement or mortar joints. This thin layer of glaze fuses, when exposed to high heat, at some lower degree 85 than the clinker concrete itself. By fusing, the glaze fills all the pores and openings of the underlying concrete and protects same from disintegration by the heat. The newly formed clinker will, by adhesion to this 90 glaze, form its own lining.

In order to aid in the forming of the lining within the cylinder casing and to assist in increasing the integrity of it as an entirety and to hold it properly in place, a series of 95 iron bars 9 arranged longitudinally of the cylinder casing and closely adjacent to its inner wall may be employed, and the concrete of the lining may be laid up around these bars. I have found it of considerable 100 advantage to have the bars twisted into spiral form as shown in the drawings. This refractory lining is arranged, as is shown, only at or near the end of the cylinder at which the high heat is provided for calcining or 105 vitrifying the cement ore.

7 is a ring or annular block of highly refractory material arranged within the ring 6 at the delivery end of the cylinder. This inner ring serves to check the flow downward 110 and outward of the ore within the cylinder and is adapted to maintain a bed of ore

within the cylinder at the delivery end thereof, of substantially uniform thickness and over which the calcined or vitrified ore which is delivered from the end of the cylinder 5 must pass.

The heat for effecting the calcining or vitrifying of the cement ores may be introduced into and generated within the firing end of the cylinder in any well known manner.

10 For the purpose of illustration I have shown a casing 12 mounted on a truck 13 which is adapted to move forward and back relative to the calcining end of the cylinder upon a trackway 14. This casing 12 is preferably lined, as indicated at 12', with a highly refractory substance. At its front end it is open and of sufficient diameter to fit over and receive the lower or delivery end of the cylinder 1. Its opposite end is closed as indicated at 12^a and through it extends the fuel delivery duct or ducts and devices indicated at 12^b. These devices may be of any well known type adapted to introduce the kind of fuel to be used in the kiln.

25 12^c is an outlet opening for the calcined or vitrified cement ore arranged through the casing 12 and adapted to lie immediately beneath the delivery end of the cylinder 1 and to permit the escape of the calcined or vitrified ore from the said cylinder directly through and from the said casing.

15 indicates a water tank arranged beneath the cylinder casing 1 near the delivery end thereof. This water tank has the forward extending inclined wall 15' which is adapted to extend out under the casing 12 when the said casing is in working position and to receive the ore delivered through the opening 12^c of the casing and to direct it into 30 the lower part of the water tank 15. The troughed bottom wall of the tank is curvilinear in shape as indicated at 15^a for a purpose to be hereinafter set forth.

16 indicates a pipe by means of which water may be fed into the said water tank, and 45 17 is an overflow pipe for escape of water from the said tank.

It will be seen that immediately after the treated clinker is delivered from the end of 50 the calcining chamber of the kiln it is practically instantly introduced directly into the water in the tank 15, and I have found it necessary to provide means for rapidly withdrawing the cement clinker from the said tank. For the purpose of illustration I have shown in the drawings a mechanism for withdrawing the cement or cement clinker from the water tank which has many advantageous features of construction and operation.

60 It consists of a rotary lifter and carrier 18 secured to and adapted to rotate with the cylinder 1. This carrier or conveyer 18 is adapted both to withdraw the cement or cement clinker from the water tank 15 and to 65 deliver it to some suitable and convenient

receptacle, such for example a hopper, as indicated at 19. It is advisable not to put this carrier or conveyer too close to the mouth of the rotary cylinder, in order to prevent steam rising from the water tank from entering with the flame into the mouth of the kiln, and causing slight reduction of the heat. 70

The conveyer 18 is preferably made in three segmental sections as indicated at 18', 18^a, and 18^b. Each segment has a bottom curved wall 18^c adapted to engage with the exterior surface of the cylinder casing 1' and to be secured thereto and has also the vertical side walls 18^d and 18^e. At one end the side walls of each segment are extended outwardly as indicated at 18^f, 18^g. The edges of the extensions are arranged parallel to each other and are non-radial. From the edges 18^g of said side walls there project inwardly flanges 18^h. The side walls of each segment near its center are also extended outwardly as indicated at 18ⁱ, 18^j, and at its other end the side walls of each segment extend outwardly as indicated at 18^k, 18^l. At this end furthermore the non-radial edges 18^m of the side walls are arranged to form a tight joint with the edges 18^e of the adjacent segment. 18ⁿ, 18° are inwardly turned flanges at the edges 18^m. The adjacent edges of adjoining segments may be detachably secured together by bolts passing through their respective inwardly turned flanges or in any other suitable manner. 19 indicate screens arranged between the side walls of the segments and preferably on non-radial lines. One of these screens is preferably arranged between each pair of segments at their adjoining edges, preferably between the flanges at these points and detachably held in place. The screens consist of an outer perforated part 19' and an inner grating 19^a. One of these screens is also arranged between the extended side walls 18ⁱ of each segment near its center, and detachably secured in place. 20 are lifting plates 110 or scoops arranged between the extended side walls of each segment and having one end adjoining the screen between said side walls. These shelves 20 preferably have inwardly projecting lugs 20 by means of which they 115 may be detachably secured to the adjacent side walls in any suitable manner, so that they may be readily detached and replaced when worn. The operation of this lifter and conveyer 18 will be readily understood. The 120 extended portion of each casing with its shelf and non-radial screen may be considered a lifting and conveying element which, during each revolution of the cylinder 1, will travel once through the water tank 15 and will 125 scoop up and withdraw from the tank any cement or cement ore above a certain height within the tank. It will be noted that the curvilinear bottom 15^a of the tank is preferably the segment of a circle struck from the 130

axis of the cylinder 1 as a center, so that as each lifting and conveying element of the conveyer 18 enters and passes through the tank, its scoop remains at substantially the same distance from the bottom of the tank and that as the said bottom is curvilinear, the shelf will tend to lift up material therefrom. As each lifting and conveying element moves out of and away from the tank any water which it may have caught up along with the cement or cement clinker will drain back into the tank through the screen 19.

In operation the cement ore to be treated is fed into the cylinder 1 and travels to the rear end thereof where it is subjected to the necessary calcining or vitrifying heat. In practice this heat is found to be 2500° and 2800° F. The clinker at this heat is then immediately dropped directly into water preferably of a temperature of about 55° F. This sudden change of temperature tends to make the clinker brittle, in some instances in fact to cause it to break up or disrupt and to make it considerably easier to grind. In order to maintain the temperature of the water at the desired point, a fresh supply of water may be caused to continuously enter the tank through the feed pipe 16 and the overflow water will drain off through the pipe 17. By thus introducing the treated cement ore directly into water at a low temperature, I have provided a process in which complicated and expensive cooling towers or various other expensive apparatus for cooling clinker is done away with, and I have substituted therefore an apparatus of low cost and extreme simplicity.

When, through wear and tear of usage, the concrete lining 8 requires replacement, this may be quickly and readily done at slight expense, avoiding thereby the delay, employment of skilled labor and expense incident to relining kilns with brick or blocks as has been heretofore the case, since it does not require a skilled bricklayer to replace the lining and the materials of construction are much cheaper than would be brick adapted for this purpose.

What I claim is:

1. In a cement kiln, the combination with a rotary cylinder, a stationary closure for one end of the cylinder having a material-discharge opening at the bottom thereof and fuel-introducing means carried by said closure, of a water tank situated beneath said material-discharge opening, and a conveyer for conducting material from said water tank.

2. In a cement kiln, the combination with a rotary cylinder, a stationary closure for one end of the cylinder having a material-discharge opening at the bottom thereof and fuel-introducing means carried by said closure, of a water tank situated beneath said material-discharge opening, and a conveyer

carried by said rotary cylinder and arranged to travel through and conduct material from said water tank.

3. The combination of a cement kiln, adapted to deliver highly heated cement clinker, a water receptacle or vessel, adapted to hold a body of water, and to receive the heated clinker directly from the combustion chamber of the kiln, and the means for quickly withdrawing the clinker from the body of water, substantially as set forth.

4. The combination of a rotary kiln, adapted to deliver the heated cement clinker, a water receptacle or a vessel immediately under the combustion chamber end of the kiln, and adapted to receive the clinker delivered by the latter, and means actuated by the kiln for engaging with the clinker in the body of water and withdrawing it therefrom, substantially as described.

5. The combination of a rotary cement kiln, a water vessel or receptacle adjacent to the kiln, and adapted to receive the cement clinker therefrom, and a clinker withdrawing device secured to and carried by the kiln, substantially as described.

6. The combination of a rotary cement kiln, a water vessel or receptacle adjacent to the kiln, and adapted to receive the clinker therefrom, and a clinker lifting device carried by the kiln, and moving through the body of water in the said receptacle, substantially as described.

7. The combination of a rotary cement kiln, a water receptacle or vessel below the delivering end of the kiln, and a series of clinker-lifting devices secured to the delivery end of the kiln, and arranged to move through the body of water in the receptacle, substantially as set forth.

8. The combination of a cement kiln, a water receptacle adjacent to the delivery end of the kiln, and having guiding devices for guiding the clinker as it moves downward through said receptacle, and a rotary clinker lifting device carried by said kiln and arranged to move through the body of water in the said receptacle, substantially as set forth.

9. The combination of a rotary cement kiln, a vessel or receptacle for the clinker, adjacent to the delivery end thereof, and a rotary clinker lifting device carried by said kiln and adapted to engage with the clinker and lift it from the said receptacle, substantially as set forth.

10. The combination of a rotary cement kiln, a water receptacle adjacent at the delivery end of the kiln and having a curved bottom wall concentric with the kiln, and a conveyer carried by said kiln and arranged to move through the body of water in said receptacle.

11. The combination of a rotary cement kiln, a water receptacle below the delivering end of the said kiln, and a series of lifting

elements carried by said kiln and arranged to move through the body of water in the said receptacle, and each lifting element comprising a scoop and a screen.

5 12. The combination of a rotary cement kiln, a water receptacle below the delivering end of the said kiln, and a series of lifting elements carried by said kiln and arranged to move through the body of water in the said

receptacle, and each comprising a detachable scoop and a detachable screen.

In testimony whereof I affix my signature, in presence of two witnesses.

OSCAR GERLACH.
